UNITED STATES PATENT OFFICE.

MICHAEL HENRY SULLIVAN, OF CARBONDALE, PENNSYLVANIA.

CARPET-HOLDER.

SPECIFICATION forming part of Letters Patent No. 569,525, dated October 13, 1896.

Application filed October 3, 1895. Serial No. 564,550. (No model.)

To all whom it may concern:

Be it known that I, MICHAEL HENRY SULLIVAN, a citizen of the United States, residing at Carbondale, in the county of Lackawanna and State of Pennsylvania, have invented a new and useful Carpet-Holder, of which the following is a specification.

This invention relates to carpet holders or fasteners of that class which are secured to the floor a short distance from the base-board and which have engaging prongs or spurs along the edge opposite to or facing the said base-board to receive and secure the carpet.

This invention aims to simplify and cheapen this class of devices and to dispense with extra fastenings for attaching the holder to the floor and to enable lighter material being employed in their manufacture.

The improvement consists of a metal strip having spurs along one edge and having the edges of the spurs recurved to prevent cutting the carpet or other floor-covering, and having points punched from the body of the strip to be driven into the floor, and having ribs or grooves spun, swaged, or otherwise provided along the edges to stiffen and strengthen the strip and enable it to withstand the strain to which it will be subjected without buckling or giving way.

For a full understanding of the invention and the advantages attendant thereupon reference is to be had to the subjoined description and the drawings hereto attached, forming a part of this specification.

In the drawings, Figure 1 is a detail view showing the invention applied. Fig. 2 is a top plan view of the holder. Fig. 3 is an edge view thereof. Fig. 4 is a cross-section on the line X X of Fig. 2. Fig. 5 is an end view of the holder.

The same numerals of reference denote corresponding and like parts in all the figures of the drawings, and in the latter 1 indicates the holder, which is formed of a strip of metal about a foot in length, and having a series of prongs or spurs 2 along one edge, and having points 3 punched or cut from the body of the strip to provide means for attaching the holder to the floor.

Grooves or ribs 4 are provided along the edges of the strip, either by spinning or swaging or in any of the usual ways, for the pur-

pose of strengthening and stiffening the strip and enabling it to be made of comparatively light metal. The points 3 will be provided in sufficient number to secure the holder to the floor in a substantial manner and will project from the nether or rear side of the holder about at right angles, and these points may have any desired shape, and, as shown, 55 their edges extend in parallelism and converge, forming blunt penetrating terminals thereto. These points extend crosswise of the strip in a line parallel with the strain upon the carpet or floor-covering, so as to sustain the 65 strain to which they will be subjected.

In reducing the invention to practice the holders are secured to the floor 5 of a room or apartment a short distance from the base-board by driving the points 3 into the floor, 70 and these holders will be spaced apart a proper distance, so as not to have the engaging spurs 2 at the ends of adjacent holders come too close together. The carpet or floor-covering 6 is drawn over the holder, and its 75 edge portion is caused to engage with the spurs or prongs 2, as indicated most clearly in Fig. 1 of the drawings.

The prongs or spurs 2 are located at one edge of the strip and are pointed, so as to 80 readily penetrate the carpet or floor-covering, and are approximately wedge-shaped in plan elevation and have their outer portions deflected or curved away from the plane of the strip, so as to facilitate the engagement 85 therewith of the carpet or floor-covering. The opposite edges of the prongs or spurs 2 are curved slightly, as shown at 7, to prevent them cutting or severing the strands of the carpet or floor-covering.

A holder constructed substantially as herein specified can be cheaply manufactured by passing a ribbon of metal between companion rolls, or the same can be struck up from a sheet by suitably-constructed dies, thereby 95 enabling the devices to be made in large quantities, so as to be placed within the reach of the user at about the same cost as the usual means commonly resorted to for attaching carpets or similar coverings to the floor.

Ifaving thus described the invention, what is claimed as new is—

An article of manufacture, a carpet holder or fastener constructed substantially as here-

in set forth, formed of a thin metallic strip having grooves or ribs extending parallel with and contiguous to its edges, and having tapering engaging spurs along one edge curving 5 upwardly and away from the plane of the strip, and having the edge portions of the said spurs recurved to prevent their cutting the carpet, and having fastening-points punched or cut from the body of the strip 10 between the parallel grooves or ribs and

extending transversely of the strip, substantially as and for the purpose specified.

In testimony that I claim the foregoing as my own I have hereto affixed my signature in the presence of two witnesses.

MICHAEL HENRY SULLIVAN.
